ANTIRAVEL KNITTED FABRICS AND
METHOD OF PRODUCING THEM

George W. Goetsch, Elkins Park, and Otto F. Smetana, Philadelphia, Pa., assignors to Quaker Hosiery Company, Philadelphia, Pa., a corporation of Pennsylvania

Application November 12, 1932, Serial No. 642,345

12 Claims. (Cl. 66—198)

This invention relates to anti-ravel knitted fabrics intended more particularly for stockings and the like.

The chief object of our invention is to render 5 knitted fabrics ravel-proof, i. e., secure against "running" lengthwise upon loop rupture, without attendant distortion of the fabrics, without sacrifice of smoothness or evenness of texture, and without impairment of the lateral elasticity so 10 essential to stocking fabrics.

The foregoing advantages we realize as hereinafter more fully explained, in a knit fabric which is characterized by plain courses, and intervening lock stitch rows each consisting of two 15 courses, one a tuck loop course, and the other a course having spaced loops doubled with each other and trebled with single loops of said tuck course.

A further object of our invention is to make 20 it possible to expeditiously and economically produce ravel-proof fabric having the indicated characteristics on flat knitting machines of the "Cotton" type such as are ordinarily used in the manufacture of full fashioned lace stockings.

25 Fig. I of the attached drawings is a diagrammatic view showing a fragment of our improved anti-ravel fabric.

Figs. II, III, IV, V, VI, VII, VIII, IX and X are fragmentary detail views showing successive steps 30 incident to the production of the fabric.

As delineated in Fig. I, the novel anti-ravel fabric of our invention comprises plain knit courses 10 consisting of loops 10a, 10b, and intervening lock stitch rows each consisting of a fabric 35 course 11 wherein adjacent loops 11a and 11b are doubled with each other, and a tuck course 12 with alternate single loops 12b of which the doubled loops 11a and 11b of the course 11 are trebled and interconnected with corresponding 40 loops 10b of the plain course 10. The loop doubling in the courses 11 is accomplished by lateral displacement of every other loop 11a laterally into coincidence with its immediate neighbor 11b; and it is to be particularly noted that in the illustrated embodiment of our invention, such loop 45 displacement is effected alternately in opposite directions in successive lock stitch rows with consequent staggering of the trebled loops of the latter between adjacent wales of the fabric. The 50 tuck loop courses 12 have been stippled merely for the purposes of distinguishing them from the other courses of the fabric.

Anti-ravel fabric characterized as above can be readily produced on an ordinary flat full fashioned stocking knitting machine, providing that

such machine is equipped with a lace attachment embodying a point bar. In Figs. II-VII, I have indicated the needles of the machine at N and the sinkers and knockovers, which cooperate with the needles in forming the fabric loops, at S and K, and the points of the lace bar at P. As shown in Fig. VIII, the lace bar which we employ has a transfer point P for every other needle N of the machine. In Figs. VIII, IX and X, alternate needles have been designated by the 10 reference character N' to facilitate the understanding of certain steps of the knitting process hereinafter described.

The fabric of Fig. I results as a consequence of 15 repetitions of a knitting cycle as follows:

In Fig. II, the needles N are raised in readiness to take freshly served yarn Y (for a tuck course 12) laid upon the nibs of the sinkers S which are at this time retracted. The yarn Y is formed into loops 12a of a course 12 over the nibs of the 20 sinkers S, as shown in Fig. III, by descent of the needles until their tops come just below the level of the sinker nibs, but the beards of said needles are not pressed at this time, so that the previously formed loops 11a of a course 11 of the fabric 25 F are not cast. After the formation of the tuck loops 12a in the manner just explained, the needles N are raised as shown in Fig. IV, carrying said loops up with them. The loops 12a cling to the needles as a consequence of being wedged in the constricted upper portions of the needle hooks, and also as a consequence of their being held in the hooks by frictional action with the needles due to the tendency of said loops to open out or spread laterally under the springiness of the yarn, which, as usual in the knitting of hosiery, is worked in the comb. The measuring of the loops 12a is accomplished without retraction of the sinkers S so that the nibs of the latter hold down the previously formed loops 11, while said 40 loops 12a are carried up with the needles N as above explained. The lace bar points P are thereupon brought up against the beards of alternate needles N as in Fig. V, and caused to descend with the needles through the previously 45 formed loops 11a as in Fig. VI. The needles and the points then rise together for a time and eventually the points separate from the needles as in an ordinary lace knitting or narrowing cycle, taking the previously formed loops 11a from alternate needles as in Figs. VII and VIII and incidentally drawing such loops over the corresponding tuck loops 12a. The lace bar is then shifted endwise to the extent of one needle and the loops 11a now on the point P are thereby 50 55

- drawn laterally over adjacent needles N'. This is followed by a second dip of the lace bar for impalement of the loops 11a on the needles N' with attendant descent of the needles, also as usual in loop transferring or narrowing operations until said loops 11a are brought below the sinkers S. The sinkers S are thereupon advanced over the loops 11a to hold them down while the needles and the points rise again together, the needles to the feeding position, and the points to their normal position of inactivity as shown in Fig. IX, with the loops 11a and 12a respectively around the shanks of the needles N' and N respectively below the needle beards.
- 15 Fresh yarn Y is then again supplied to all the needles as shown at Fig. IX whereupon said needles descend to form another plain course 10 from said yarn as shown in Fig. X. Accordingly, the loops 10a of the new course 10 are drawn through the single loops 12a incidentally cast by the needles N, while the loops 10b are drawn through the trebled loops 11a, 11b and 12b concurrently cast by the needles N', all as shown in Fig. X. Finally another course is knit 20 to provide loops 11a, 11b in readiness for the starting of the next cycle which is performed in exactly the same way except for loop transferring in the opposite direction as described in connection with Fig. I. If desired however, the transferring may be done always in the one direction throughout the fabric, i. e., either always to the right, or always to the left.
- 25 By varying the spacing of the transfer points P and the extent of shifting of the point bar, corresponding modifications may obviously be determined in the fabric knit according to our improved method as defined in the appended claims.
- 30 Having thus described our invention, we claim:
- 40 1. Anti-ravel fabric comprising plain knit courses; and intervening lock stitch rows each composed of two courses, and one having contiguous loops thereof doubled with each other, and the other course having certain loops thereof trebled with the doubled loops of the first course.
- 45 2. Anti-ravel fabric in accordance with claim 1 wherein the trebled loops of successive lock stitch rows are staggered between the wales of the fabric.
- 50 3. Anti-ravel fabric comprising plain knit courses; and intervening lock stitch rows each composed of two courses, one having contiguous loops thereof doubled with each other, and the other course having alternate loops thereof trebled with the doubled loops of the first course.
- 55 4. Anti-ravel fabric in accordance with claim 3 wherein the trebled loops of successive lock
- stitch rows are staggered between wales of the fabric.
5. The method of producing anti-ravel fabric which comprises knitting a course of loops; then forming a course of tuck loops; then doubling contiguous loops of the first course and trebling them with single loops of the tuck course; then knitting a plain course; and continuously repeating the described cycle. 5
6. The method of producing anti-ravel fabric 10 in accordance with claim 5 and causing the trebled loops of successive lock stitch rows to be staggered between wales of the fabric.
7. The method of producing anti-ravel fabric which comprises knitting a course of loops; then forming a course of tuck loops; then doubling contiguous loops of the first course and incidentally trebling them with alternate loops of the tuck course; then knitting a plain course; and continuously repeating the described cycle. 20
8. The method of producing non-ravel fabric in accordance with claim 7 and causing the trebled loops of successive lock stitch rows to be staggered between wales of the fabric.
9. The method of producing anti-ravel fabric 25 on a flat knitting machine having a lace bar with points to correspond with spaced needles, which comprises knitting a course of loops on the needles of the machine; then forming a row of tuck loops on the needles; then, by means of the 30 points of the lace bar, drawing loops from the corresponding needles over the tuck loops on such needles and transferring them to other needles with incident trebling of the loops so doubled with single loops of the tuck course held 35 on the needles; then drawing a plain course of loops; and continuously repeating the described cycle.
10. The method of producing anti-ravel fabric on a flat knitting machine in accordance with 40 claim 9, and causing the trebled loops of successive lock stitch rows to be staggered between wales of the fabric by shifting of the point bar in opposite directions.
11. Anti-ravel fabric comprising plain knit 45 courses; and intervening lock stitch rows each composed of two courses and having contiguous wale loops of one such course doubled with each other and trippled with single loops of the other course. 50
12. Anti-ravel fabric in accordance with claim 11 wherein the trebled loops of successive lock stitch rows are staggered between the wales of the fabric.

GEORGE W. GOETSCH. 55
OTTO F. SMETANA.
